TO UNIVERSAL OIL PRODUCTS COMPANY, OF CHICAGO, ILLINOIS, A CORPORATION
OF SOUTH DAKOTA.

APPARATUS FOR TREATING OIL.

Application filed October 8, 1920. Serial No. 415,837.

To all whom it may concern:

Be it known that we, GUSTAV EGLOFF and HARRY P. BENNER, both citizens of the United States, residing in the town of Independence, county of Montgomery, and State of Kansas, have invented certain new and useful Improvements in Apparatus for Treating Oil, of which the following is a specification.

10 This invention relates to an apparatus for treating oil, and refers more particularly to an apparatus which is adapted for the cracking of petroleum oil to produce from the relatively heavy constituents thereof 15 lighter or lower boiling point constituents.

The object of the invention is to provide a construction in which the heating chamber permits of a bullet-like velocity of the oil in its passage through the heating chamber 20 or coil while at the same time obtaining a maximum heating area from the same lengths of tubes, as for example, more than four times the heating area of plain tubes. This will greatly cut down the construction 25 cost; the tubes are spirally corrugated tubes as shown more clearly in the drawings:

In the drawings:

Fig. 1 is a view, partly in side elevation and partly in vertical section, of our improved apparatus.

Fig. 2 is an enlarged sectional detail view of one of the spirally corrugated heating elements.

Referring in detail to the drawings, 1 designates the furnace provided with grate 2, bridge wall 3, burner 4 and stack 5. In the furnace is mounted the heating element which is one of the novel features of the construction and consists of a coil or a plurality of coils or pipes 6, each of which takes the form of a spirally corrugated tube 7 as shown more clearly in Fig. 2. The inlet side of the coil is connected to feed line 8, having a valve 9 and leading to charging 45 pump 10. The inlet side of the pump is connected by pipe 11 having valve 12 to any suitable source of raw oil supply. The outlet side of the heating coil is connected by transfer line 13 to a vapor or expansion 50 chamber 14. This expansion chamber 14 is provided with vapor outlet 15 having

throttle valve 16 and extending into the lower end of a dephlegmator 17. The upper end of the pipe 15 is provided with a spaced cap member 18, to permit the vapors 55 to pass out of the pipe 15 into the condenser or dephlegmator while preventing the reflux condensate from falling back into the pipe 15. Reflux condensate passes out of the dephlegmator back to the heating coil 60 through pipe 19 regulated by throttle valve 20. The upper part of the dephlegmator is connected by the vapor line 21 having a throttle valve 22 to condenser coil 23 seated 65 in condenser box 24. The lower end of the coil 23 is connected by pipe 25 having throttle valve 26 to the upper end of receiver 27. This receiver 27 has the usual liquid level gauge 28, pressure gauge 29 and liquid and gas outlets 30 and 31, controlled by valves 70 32 and 33 respectively.

From the foregoing it will be seen that the oil to be treated can be continuously fed to the heating zone and caused to have a spirally revolving motion as it passes 75 through the heating coil. The arrangement is such as to give a maximum heating area as referred to and at the same time, permit of the raw oil being fed at high velocity through the heating chamber or other heating element.

In carrying out a process to crack oil with this apparatus, gas oil, for example, may be heated to a temperature of 750 degs. F. in the coil and subjected to a uniform pressure 80 of 100 pounds throughout the system or differential pressures may be obtained by regulating the valves shown.

We claim as our invention:

In an apparatus for cracking hydrocarbon oil, the combination with a furnace of a coil therein for the passage of oil, said coil consisting of a plurality of spirally corrugated tubes passing through the furnace and through which the oil must pass, a vapor 85 chamber in communication with said tubes, a dephlegmator communicating with said vapor chamber, and a condenser communicating with said dephlegmator.

GUSTAV EGLOFF.
HARRY P. BENNER.
